EDWARD M. GOODEBODY, OF BROOKLYN, NEW YORK, ASSIGNOR TO THE INTERTYPE CORPORATION, OF NEW YORK, N. Y., A CORPORATION OF NEW YORK.

LINOTYPE-MACHINE.

1,192,620.

Specification of Letters Patent. Patented July 25, 1916.

Application filed November 30, 1912. Serial No. 734,362.

To all whom it may concern:

Be it known that I, EDWARD M. GOODEBODY, a subject of the King of Great Britain, and a citizen of the Dominion of Canada, now 5 residing at Brooklyn, in the county of Kings and State of New York, have invented certain new and useful Improvements in Linotype-Machines, of which the following is a specification.

10 The present invention relates to improvements in Linotype machines and more particularly to the escapement mechanism which controls the delivery of matrices from the magazine.

15 The primary object of the invention is to provide spring means for restoring the escapements to normal position, such means being very compact, thus avoiding encroachment upon or interference with other parts 20 of the machine, and the strength of the spring action upon all of the escapements will be uniform, the springs will not be liable to exceed their limit of elasticity, and also the spring means embodying the present 25 invention is simple in construction, inexpensive to manufacture, and capable of being readily applied and removed.

To these and other ends, the invention consists in certain improvements, and combinations and arrangements of parts, all as 30 will be hereinafter more fully described, the novel features being pointed out particularly in the claims at the end of the specification.

35 In the accompanying drawing:—Figure 1 represents a vertical section of the lower or delivery end of the magazine of a Linotype machine embodying the present invention; Fig. 2 is a bottom plan view of one of the 40 lower corners of the magazine.

Similar parts are designated by the same reference characters in the several views.

The present invention is applicable generally to line composing and type casting 45 machines of the class embodying a magazine having channels or cells containing matrices and provided with escapements controlling the delivery of the matrices from the respective channels, the invention being especially 50 applicable to the escapement mechanism of Linotype machines and may be used in connection with various forms of escapement mechanism.

In the present instance, the magazine 1 is 55 of the usual or well-known construction, it having upper and lower grooves 2 which

form channels or cells along which the matrices M may gravitate toward the lower or delivery end of the magazine, the latter being shown in the inclined position which it 60 occupies on the machine. The lugs m of the matrices slide in the upper and lower grooves of the magazine as in the machines commonly used.

The invention is shown in the present instance as applied to escapement mechanism such as that disclosed and claimed in the co-pending application of Thomas S. Homans, Serial No. 707,926, filed July 5, 1912, although it is to be understood that 70 the present invention is not restricted to an escapement mechanism of this particular type.

The escapement mechanism to which the invention is applied in the present instance 75 may be briefly described as embodying a bar or rail 3 which is secured to the under side of the magazine, and the upper face of this bar is grooved to form uninterrupted continuations of the lower grooves in the magazine. The lower side of the bar or rail 3 is of substantially semi-cylindrical form and it is provided with a series of grooves 4 which are of semi-circular form. These 80 grooves 4 converge toward the delivery end 85 of the magazine and are preferably arranged directly below and in alignment with the converged matrix channels of the magazine. An escapement 5 is arranged to oscillate in each semi-circular groove 4, the escapement being substantially semi-circular 90 in form and its ends 6 and 7 serve as dogs or pawls to coöperate with the lugs of the matrices in a manner to cause the delivery of one matrix from its respective magazine 95 channel upon each actuation of the escapement by manipulation of the keyboard, a series of reeds or key-rods 8 being provided which are elevated from the full line position to the dotted line position as shown in 100 Fig. 1 when the corresponding key of the keyboard is operated, each escapement 5 having an operating lug 9 upon which the respective reed or key-rod 8 operates.

Each escapement is provided with a 105 spring-actuated member 10 which serves to restore the corresponding escapement to normal or initial position after each actuation thereof. Preferably, these members are composed of levers which are pivotally 110 mounted on a single or common rod 11, the latter being supported by the rail 12 at the

under side of the magazine and serves as a common pivot. One end of each lever is provided with an arm 13 upon which a spring 14 presses, and the other end of each lever has a portion 15 which co-operates with a lug or projection 16 on the respective escapements. Preferably, the spring-actuated members operate in an upward direction upon the forward ends of the escapements, 10 this arrangement being advantageous in that the key-rods or reeds 8 and the spring-actuated members both act to retain the escapements in engagement with the semi-circular bearings provided by the groove in the 15 under side of the bar or rail 3, and also this arrangement of the spring-actuated members avoids interference with the operation of the reeds or key-rods. The springs 14 which act upon the members 10 are preferably contained in pockets 17 which may be conveniently formed in the rail 12 at the 20 under side of the magazine and adjacent to the mouth or delivery end thereof, this arrangement of the springs being very compact and it enables the springs and the actuating members to occupy the limited 25 space between the escapements and the mouth or delivery end of the magazine without encroaching upon the guides through 30 which the matrices pass when they are delivered from the magazine.

Experience has demonstrated that helical springs of round wire are more uniform in their strength and resilience than springs 35 of any other form, and that a maximum degree of action can be obtained from springs of this type without danger of exceeding their limit of elasticity.

The present invention provides compact, 40 simple and inexpensive means for utilizing helical springs for the purpose of restoring the magazine escapements to normal or initial position, and the chambers which inclose and guide these helical springs may 45 be readily formed by boring into the lower end of the rail 12. The present invention also provides simple and improved means for preventing dropping of the escapements 50 from their bearings in the bar 3 when the pressure of the reeds or key-rods 8 is relieved, such means consisting in the present

instance of a guard 18 which is preferably segmental in form to fit against the cylindrical lower side of the bar 3 and to co-operate with the semi-circular lower edges 55 of the escapements. This guard is preferably held in operative position by screws 19 which are tapped into the bar 3, and the heads of these screws overlie the longitudinal edges of the guard. This arrangement 60 enables the guard 18 to be readily removed by sliding it longitudinally between the screws 19, removal of the screws being unnecessary, and when the guard has been removed, all of the escapements can be readily 65 removed for cleaning or replacing.

While the matrix-containing channels of the magazine converge toward the mouth or delivery end of the magazine and the escapements are preferably disposed in the 70 same planes with their respective channels, the members which serve to transmit the action of the springs to the respective escapements may be arranged in parallelism, as shown, thus simplifying the construction 75 and reducing the cost of manufacture thereof.

I claim as my invention:—

1. In a linotype machine, the combination of a matrix-containing magazine, a semi-cylindrical bar having semi-circular grooves in its under side, a series of matrix-controlling escapements mounted in the semi-circular grooves in said bar, and a guard detachably fitted to the outer surface of said bar and 80 engaging the escapements to retain the escapements in place. 85

2. The combination of a matrix magazine, a bar arranged at the under side thereof, a set of substantially semi-circular matrix-controlling escapements co-operative with the under side of said bar, and a guard slidably longitudinally of said bar and co-operative with the escapements to retain them in operative position. 90 95

In testimony whereof I have hereunto set my hand in presence of two subscribing witnesses.

EDWARD M. GOODBODY.
